UNITED STATES PATENT OFFICE

HARLEY J. EARL, OF DETROIT, MICHIGAN, ASSIGNOR TO GENERAL MOTORS CORPORATION, OF DETROIT, MICHIGAN, A CORPORATION OF DELAWARE

DESIGN FOR A HEAD-LAMP MEDALLION

Application filed May 2, 1930. Serial No. 35,478. Term of patent 14 years.

To all whom it may concern:

Be it known that I, HARLEY J. EARL, a citizen of the United States, and a resident of Detroit, county of Wayne, State of Michigan, have invented a new, original, and ornamental design for Head-Lamp Medallion, of which the following is a specification, reference being made to the accompanying drawing, forming a part thereof.

I claim:

The ornamental design for a headlamp medallion, as shown.

HARLEY J. EARL.
